tion, New York, N.Y., a corporation of Delaware

Application April 18, 1958, Serial No. 50,517

Term of patent 14 years

(Cl. D64—11)

FIG.1

FIG. 2

FIG. 3

Figure 1 is a front perspective view of a typewriting machine showing our new design;

Figure 2 is a rear perspective view; and

Figure 3 is a left-hand side elevation thereof.

The machine when viewed from the right is substantially similar in appearance as that disclosed in Figure 3.

The dominant features of our design reside in the portions of the machine shown in solid lines.

We claim:

The ornamental design for a typewriting machine, as shown and described.
